CLAIM

We claim the ornamental design for a display screen or a portion thereof with graphical user interface, as shown and described.

DESCRIPTION

FIG. 1 is a display screen or portion thereof with graphical user interface showing our new design according to an embodiment; and,

FIG. 2 is a display screen or portion thereof with graphical user interface showing our new design according to an embodiment.

The dashed broken line in the perimeter of the drawings illustrates a display screen or portion thereof and forms no part of the claimed design. The remaining broken lines illustrate portions of the graphical user interface and form no part of the claimed design.

1 Claim, 2 Drawing Sheets
